Primary Examiner — Ruth McInroy(74) *Attorney, Agent, or Firm* — Morrison & Foerster LLP**CLAIM**

We claim the ornamental design for a part of a vacuum cleaner, as shown and described.

DESCRIPTION

FIG. 1 is a perspective view of a part of a vacuum cleaner showing our new design;
 FIG. 2 is a front view thereof;
 FIG. 3 is a rear view thereof;
 FIG. 4 is a side view thereof;
 FIG. 5 is a side view from the side opposite that of FIG. 4;
 FIG. 6 is a plan view thereof from above; and,
 FIG. 7 is a plan view thereof from below.
 The details shown in broken lines form no part of the claimed design.
